HINGE ASSEMBLY

Floyd G. Gould, Detroit, Mich., assignor to Ferro Stamping & Manufacturing Company, Detroit, Mich., a corporation of Michigan

Application May 26, 1941; Serial No. 395,299

5 Claims. (Cl. 16—163)

This invention relates generally to hinges and refers more particularly to improvements in hinges of the type employed to displace a movable part relative to its support during swinging movement of the movable part.

Although the hinge forming the subject matter of this invention may be advantageously used in practically any instance where it is desired to bodily displace a movable part relative to its fixed support during swinging movement of the movable part, nevertheless, it finds particular utility when employed in the manufacture of motor vehicles for connecting the rear edge portion of an "alligator" type hood to its support.

A hinge constructed in accordance with this invention is especially advantageous for the above purpose because it is not only concealed from view in the closed position of the hood but, in addition, is of simple, lightweight construction capable of being inexpensively manufactured, assembled and installed.

Another object of this invention is to provide a hinge having spring means for assisting in raising the hood to its open position and for holding the hood in the latter position.

A further object of this invention is to provide a hinge of the above type wherein the several parts thereof, including the counterbalancing spring means, form a unit with a bracket which is capable of being readily attached to the fixed support for the hood. As a result, the hinge may be assembled at one point independently of the hood and readily attached as a unit in the field.

A still further feature of this invention is to provide a hinge so constructed that the spring means coacts with the other parts of the hinge to hold the hood down against the hood lacings usually provided on the fixed hood support. As a result, wear of the hood lacings is compensated for and rattling of the hood is prevented.

The foregoing, as well as other objects, will be made more apparent as this description proceeds, especially when considered in connection with the accompanying drawing, wherein:

Figure 1 is a side elevational view of a hinge assembly constructed in accordance with this invention and showing the parts of the hinge in two different positions;

Figure 2 is a sectional view taken on the line 2—2 of Figure 1; and

Figure 3 is a sectional view taken on the line 3—3 of Figure 1.

Upon reference to Figure 1, it will be noted that the reference character 10 indicates a mov-

able part which, in the present instance, may be considered a hood for a motor vehicle, and the reference character 11 designates, generally, a hinge assembly embodying the features of the present invention. The hood 10 is of the type adapted to be swung upwardly from the front end thereof in order to gain access to the space beneath the hood and, accordingly, the rear end of the hood is hingedly connected to a fixed part 10 of the vehicle. In the present instance, two hinge assemblies 11 are provided for connecting the rear end of the hood to fixed parts of the vehicle and these hinge assemblies are located at opposite sides of the hood so as to be concealed from view when the hood is in its closed position. However, since both hinge assemblies are identical, only one is shown and described herein.

In detail, the hinge assembly 11, shown in the several figures of the drawing, includes a bracket 20 12 in the form of a plate apertured at spaced points to permit the same to be rigidly secured to a fixed part (not shown) of a vehicle and adapted to support all of the several elements of the hinge so that a unitary construction is provided. A link 13 is pivotally connected intermediate the ends thereof to a raised portion 14 on the lower end of the bracket 12 by means of a pin 15, and the rear end of the link 13 is pivotally connected to the hood, or movable part, 10 by means of a pivot pin 16. A second link 17 has the upper end thereof pivotally connected to a depressed portion 18 on the upper part of the bracket 12 by means of a pin 19, and the lower end of the link 17 is pivotally connected to a third link 20 by means of a pin 21. The link 20 is also pivotally connected to the forward end of the link 13 by means of a pin 22.

The forward end of the link 13 extends laterally at substantially right angles to the link 40 13 so that when the hood, or part, 10 is in its lowermost position, the pivot pin 22 assumes a position above the pivot pin 15. The above relative positions of the parts are shown by the full lines in Figure 1, and it will be observed from the dotted line position of these parts that the pivot 22 moves from a position above the pivot 15 to a position below the latter when the hood, or part, 10 is swung to its raised position.

In accordance with the present invention, movement of the part 10 to its raised position is assisted by a counterbalancing spring 25. The spring 25 is of the "clock-type" having the inner end fixed to the pivot pin 21 and having the outer end looped around the upper side of a

shoulder 23 on the link 20. The arrangement is such that when the links are swung from the dotted line positions to the full line positions shown in Figure 1, the spring 25 is wound, or tensioned, and exerts a downward force on the link 20. Inasmuch as the pivot pin 22 assumes a position above the pivot pin 15 when the hood, or part, 10 is in its lowermost position, the downward force exerted by the spring on the link 20 tends to hold the hood, or part, 10 in its lowermost position against the flexible seal 24. It will be noted, however, that when the hood, or part, 10 is in its lowermost position, the pivot pin 22 is located in close proximity to the pivot pin 15 above the latter so that initial raising movement of the part 10 is sufficient to swing the pivot pin 22 below the pivot pin 15 whereupon continued raising movement of the part 10 is assisted by the spring 25. In this connection, attention is called to the fact that the link 20 is provided with a portion 27 which extends beyond the pivot 21 and has a shoulder 28 for engagement with the front edge of the link 17 intermediate the ends of the latter. The shoulder 28 forms a stop to limit the movement of the linkage to the dotted line position shown in Figure 1.

It will be observed from the above that the hood, or part, 10 is not only swung upwardly by a movement of the linkage from the full line to the dotted line positions shown in Figure 1 but, is also displaced forwardly. In the present instance, this is highly advantageous in that it permits the rear end of the hood to clear the cowl (not shown) of the vehicle during swinging movement of the hood. In this connection, it is further pointed out that the travel of the hood, or part 10, is controlled by a link 29 having the lower end pivotally connected to the bracket 12 by the pin 19 and having the upper end pivotally connected to the hood, or part, 10 at a point spaced forwardly from the pivot pin 16.

Thus, from the foregoing, it will be observed that I have provided a combined hinge and counterbalancing means which forms an assembly capable of being readily attached as a unit. It will also be noted that the several parts of the hinge are of simple construction and lend themselves to economical manufacture.

What I claim as my invention is:

1. A hinge for pivotally connecting a movable part to a fixed part in a manner to swing the movable part longitudinally and upwardly relative to the fixed part, said hinge comprising a link having one end pivoted to the movable part and having a portion intermediate the ends pivoted to the fixed part, a pair of links having the adjacent ends pivotally connected together and having the outer ends respectively pivoted to the other end of the first link and to the fixed part, a spiral spring having the inner end secured to the pivotal connection between the adjacent ends of said pair of links and having the outer end engaging one of the links of said pair, said spring and links being so arranged that lowering the movable part relative to the fixed part winds the spring so that the latter assists movement of the movable part to its raised position, and a link having the opposite ends respectively pivoted to the fixed and movable parts to control the movement of the latter part relative to the fixed part.

2. A hinge for pivotally connecting a movable part to a fixed part in a manner to swing the movable part longitudinally and upwardly relative to the fixed part, said hinge comprising a

link having one end pivoted to the movable part and having a portion intermediate the ends pivoted to the fixed part, a second link having the upper end pivoted to the fixed part, a third link having one end pivoted to the lower end of the second link and having the other end pivoted to the first link, a spiral spring having the inner end secured to the pivotal connection between the second and third links and having the outer end engaging the third link intermediate the ends of the latter, the pivotal connection between the first and third links being located above the point of pivotal connection between the first link and fixed part in the lowermost position of the movable part so that the spring acts to hold the movable part in its lowermost position and said pivotal connection being movable to a position below the point of pivotal connection of the first link with the fixed part as the movable part is raised so that the spring assists in raising the movable part, and means between the bracket and movable part coating with said links to swing the movable part about the pivotal connection between the first link and movable part.

3. A hinge for pivotally connecting a movable part to a fixed part in a manner to swing the movable part longitudinally and upwardly relative to the fixed part, said hinge comprising a bracket secured to the fixed part, a link having one end pivoted to the movable part and having a portion intermediate the ends pivoted to said bracket, a second link having the upper end pivoted to the bracket, a third link having one end pivoted to the lower end of the second link and having the other end pivoted to the first link, a spiral counterbalancing spring having the inner end fixed to the pivotal connection between the second and third links and having the opposite end connected to the third link intermediate the ends of the latter, the pivotal connection between the first and third links being located above the point of pivotal connection between the first link and fixed part in the lowermost position of the movable part so that the spring acts to hold the movable part in its lowermost position and adapted to move to a position below the point of pivotal connection of the first link with the fixed part as the movable part is raised so that the spring assists in raising the movable part, and a link having one end pivotally connected to the bracket and having the opposite end pivotally connected to the movable part at a point spaced from the pivotal connection of the first link with the movable part for controlling swinging movement of the said movable part.

4. A hinge for pivotally connecting a movable part to a fixed part in a manner to swing the movable part longitudinally and upwardly relative to the fixed part, said hinge comprising a bracket secured to the fixed part, a link having one end pivoted to the movable part and having a portion intermediate the ends pivoted to the bracket, a second link having the upper end pivoted to the bracket, a third link having one end pivoted to the lower end of the second link and having the other end pivoted to the first link, a spiral counterbalancing spring having the inner end secured to the pivotal connection between the second and third links and having the outer end engaging the third link intermediate the ends thereof in a manner to assist movement of the movable part to its raised position, and an additional link having one end pivotally connected to the bracket and having the other end

pivotedly connected to the movable part at a point spaced from the pivotal connection between the first link and movable part to control swinging movement of said movable part.

5. A hinge for pivotedly connecting a movable part to a fixed part in a manner to swing the movable part longitudinally and upwardly relative to the fixed part, said hinge comprising a bracket secured to the fixed part, a link having one end pivoted to the movable part and having a portion intermediate the ends pivoted to said bracket, a second link having one end supported on the bracket for shifting movement relative

to the bracket and having the other end pivotedly connected to the other end of the first link, a spiral spring having the inner end secured to the shiftable end of the second link and having the outer end engaging the second link intermediate the ends thereof in a manner to assist the swinging movement of the movable part to its raised position, and means connecting the bracket to the movable part and operable to swing the movable part about the pivotal connection between the first link and movable part.

FLOYD G. GOULD.
